UNITED STATES PATENT OFFICE.

FRANS T. STRÖBECK, OF BEACHMONT, MASSACHUSETTS, ASSIGNOR TO THE SINGER
MANUFACTURING COMPANY, A CORPORATION OF NEW JERSEY.

SEWING-MACHINE.

1,152,667.

Specification of Letters Patent. Patented Sept. 7, 1915.

Application filed December 8, 1913. Serial No. 805,228.

To all whom it may concern:

Be it known that I, FRANS T. STRÖBECK, a citizen of the United States, residing at Beachmont, in the county of Suffolk and 5 State of Massachusetts, have invented certain new and useful Improvements in Sewing-Machines, of which the following is a specification, reference being had therein to the accompanying drawings.

10 This invention has for its primary object to provide effective means for fulling the margin of knit goods and applying thereto a binding tape.

As preferably constructed, the ruffling 15 mechanism comprises a vibratory arm with means for varying its amplitude of vibration, and detachable coupling means whereby an independently movable swinging arm carrying the ruffling blade may be operatively connected with or disconnected from 20 said arm. Arranged adjacent and at one side of the path of movement of the ruffling blade is a binder, while beneath said path of movement is a work-supporting plate 25 preferably formed with convergent guide-ribs inclined relative to the direction of movement of the ruffling blade and toward the binder.

The invention will be understood by reference to the accompanying drawings, in 30 which—

Figure 1 is an end view of a sewing machine embodying the present improvement, and Fig. 2 a perspective view of a portion 35 thereof with the bracket-arm omitted. Fig. 3 is a perspective view of the ruffling blade, the ribbed work-supporting plate and the binder. Fig. 4 is a front end view of the work-supporting plate and the binder with 40 the body fabric and the binding tape in position. Fig. 5 is a perspective view of a section of knit goods with the binding applied thereto. Fig. 6 is a detail perspective view showing the preferred adjustment of 45 the ruffling blade stop member upon the blade-carrying arm.

The sewing machine frame is constructed with the usual bed-plate 1 and bracket-arm 2 in the overhanging portion of which is 50 journaled the main-shaft 3 to the forward end of which is operatively connected the reciprocating needle-bar 4 carrying the needle 5 cooperating with the complementary stitch-forming mechanism beneath the bed-plate.

The feeding mechanism is constructed and operated substantially as disclosed in my United States Patent No. 986,652, of March 14, 1911, comprising the lower feed-dog 6 and the upper feeding-foot 7 secured to the 60 swinging bar 8 with its apertured upper end embracing the stud-screw 9 sustained by the angle-lever 10. This angle-lever is provided with a lateral arm carrying the stud-screw 11 which is embraced by the apertured lug 65 12 of the collar 13 fixed upon the presser-bar 14 which carries the presser-foot 15 disposed in advance of the feeding foot 7 and provided with the usual needle-hole. The upwardly extending arm of the elbow-lever 10 carries a stud-screw 16 connected by the link 17 with the stud-screw 18 upon the upwardly extending crank-arm 19 secured upon the rock-shaft 20 journaled upon the head of the overhanging bracket-arm. 70 The rock-shaft 20 has fixed thereon a second crank-arm 21 carrying the stud-screw 22 embraced by the apertured extremity of the eccentric-rod 23 provided with a strap 24 which is fitted upon the actuating eccentric 25 fixed upon the main-shaft 3. From the 75 means just described the presser-feet 7 and 15 derive alternating lifting movements.

The shank of the feeding foot 7 is provided with a lug carrying the pin 26 connected by the link member 27 with the pivotal pin 28 sustained by the depending arm 29 of the upper feed rock-shaft 30 which is in practice connected with the lower feeding mechanism and from which the feeding 80 foot 7 derives its work-advancing movements.

Intermediate its ends the eccentric-rod sustains the screw-pin 31 embraced by the apertured upper end of the depending link 90 32 connected at its opposite end by the screw-pin 33 with the lateral crank-arm 34 fixed upon the rear end of the rock-shaft 35 disposed parallel with and beneath the rock-shaft 20. This rock-shaft has upon its opposite end the depending arm 36 formed with a slot 37 which is overlaid by the swinging arm 38 having the slot 39 and sustained at its upper end upon the fulcrum-pin 40 mounted in the head of the bracket-arm adjacent the rock-shaft 20. A coupling screw 41 is employed in a manner well known to pivotally connect the slotted arms 36 and 38, the shank of such screw passing 100 through the slots in said arms and being 105 110

adapted to be clamped in different positions of adjustment therein relatively to the actuating rock-shaft 35.

Journalized upon the fulcrum-pin 40 is the ruffler-blade carrying arm 42 carrying at its free end the stud-screw 43 upon which is mounted the rocking plate 44 sustaining the ruffling blade 45 which is pressed normally downward by means of the spring 46 embracing the stud-screw 43 and having one arm connected with the plate 44 and the other arm in engagement with the stop-lug 47 of the rigid finger 48 clamped adjustably in position by means of the stud-screw 43.

15 The rock-shaft 20 and fulcrum-pin 40 are mounted in a common bearing-boss secured to the head of the bracket-arm 2, the inner face of the arm 42 resting against the end of such bearing-boss and both this arm and 20 the overlying swinging arm 38 being confined against movement endwise of the fulcrum-pin 40 by the nut 40' applied to the end of the fulcrum-pin.

The arm 42 has in its forward face at the 25 rearward edge the inclined notch 49 and adjacent aperture 50 adapted to be engaged by the extremity of the latch-pin 51 journalized in a socket 52 of the bracket-piece 53 which is secured to the swinging arm 38 and 30 pressed normally outward by means of the spring 54. As represented in Fig. 2, the arm 42 is disconnected from the arm 38, being held in retracted position by means of the spring 55 hooked at one end in the aperture 56 of said arm and secured at the opposite end by means of the stud-screw 57 to the head of the bracket-arm.

By pressing the arm 42 downwardly, the 40 bottom of the inclined notch 49 presses back the latch-pin 51 which snaps into the aperture 50 to couple the arms 38 and 42 together for a ruffling operation. The disengagement of the latch-pin by retraction of its head 51' causes the uncoupling of the 45 ruffling-blade carrying arm which returns to retracted position under the action of its spring 55. By provision of an arm for the ruffling blade separate from the swinging arm 38 and providing detachable connecting means between such arms the ruffling blade may be connected with and disconnected from its actuating mechanism without disarrangement of the adjustment 50 of the coupling pin 41 which determines the amplitude of the ruffling movements.

Secured upon the sewing machine bed-plate by means of screws 58 entering the slot 59 therein is the shank 60 of the binding guide 61 having the usual U-shaped channel 60 which in practice embraces the laterally projecting portion 45' of the ruffling blade 45. Beneath the path or range of movement of the ruffling blade is disposed the work-supporting plate 62 which is shown provided 65 with the aperture 63 entered by the fasten-

ing screws 64 by means of which it is secured upon the bed-plate in advance of the sewing machine throat-plate 65 and at the side of the binding guide 61. The forward portion of this plate 62 adjacent the binder 70 is upwardly offset at 62' (Fig. 4) to provide clearance for the lower limb of the binder and permit the lower ply of the binding tape *t* to be directed freely beneath the margin of the body fabric *f*. This offset portion of the work-supporting plate is provided with the convergent standing guide-ribs 66 which are inclined relatively to the direction of feed and of movement of the ruffling blade toward the binding guide. 80 These ribs are so arranged and proportioned that they support the body fabric adjacent the binding guide under the action of the ruffling blade and serve to crowd the same edgewise into contact with the middle portion of the binding tape within the guide so as to insure uniformity in the overlap of the upper and lower plies of the tape upon the corresponding faces of the fulled body fabric. It is of course not essential 90 to the present improvement that these guide-ribs be disposed upon a separate plate as they may obviously be formed directly upon the throat-plate, in so far as the performance of their specific function is concerned. 95

In the use of the machine, a binding may be applied to an unruffled or unfulled body fabric when the ruffling blade carrying arm 42 is disconnected, as represented in Fig. 2, but when the latter is coupled, as indicated 100 in Fig. 1, the ruffling or fulling operation is added. By the mechanism described, the parts are so proportioned and timed that the ruffling blade advances simultaneously with but more rapidly than the feeding foot 105 7 while the non-feeding presser-foot 15 is raised, and the retrograde movement of such parts occurs when the foot 15 is pressed upon the goods and the foot 7 is lifted. As the work advances under the ruffling action 110 to crowd the same beneath the needle and between the edge of the ruffling blade and the feeding foot 7, it is simultaneously forced by the guide-ribs 66 between the upper and lower limbs of the binder where- 115 by it is maintained in contact with the middle portion of the binding tape during the stitching operation.

The product of the mechanism, as thus described, is represented in Fig. 5, wherein 120 the margin of the body fabric *f* is shown fulled and secured by means of the line of stitching *s* between the folded superposed plies of binding tape *t*.

As represented in Fig. 6, the rigid finger 125 48 is set in such position upon the blade-carrying arm 42 that its stop-lug 47 arrests the rocking plate 44 under the action of the spring 46 in a position substantially parallel with that represented in Fig. 1, but with 130

the blade 45 extended upwardly from the work-supporting plate. By this means, the disconnection of the arm 42 from the vibratory arm 38 not only permits such arm to swing upwardly to disengage the ruffling blade from the work, but causes the blade to turn upon its fulcrum-stud 43 so as to direct its serrated work-engaging edge upwardly away from the work to prevent accidental contact with the work in the removal of the latter from the machine.

Having thus set forth the nature of the invention, what I claim herein is:—

1. In a sewing machine, the combination with stitch-forming and feeding mechanisms, of ruffling mechanism comprising a vibratory arm, a swinging arm overlying the same and having a fulcrum remotely disposed relatively to that of the other arm, means adjustable toward and from said fulcrum for pivotally connecting said arms together at different points, means connected with and adapted to impart to said vibratory arm operative movements, a ruffling blade carrying arm having a fulcrum coaxial with that of said swinging arm, a detachable connection between said coaxially fulcrumed arms, means for maintaining said ruffling-blade carrying arm retracted from operative position and disconnected from said swinging arm and a ruffling blade sustained by said blade-carrying lever.

2. In a sewing machine, the combination with stitch-forming and feeding mechanisms, of ruffling mechanism comprising a vibratory arm, a swinging arm overlying the same and having a fulcrum remotely disposed relatively to that of the other arm, means adjustable toward and from said fulcrum for pivotally connecting said arms together at different points, means connected with and adapted to impart to said vibratory arm operative movements, a ruffling blade carrying arm having a fulcrum coaxial with that of said swinging arm, means for confining said arms against movement lengthwise of their fulcrums, a spring-pressed pin mounted upon one of said arms for engaging the other for locking said arms

detachably together, means for maintaining 50 said ruffling-blade carrying arm retracted from operative position and disconnected from said swinging arm, and a ruffling blade carried by said blade carrying arm.

3. In a sewing machine, the combination 55 with stitch-forming and feeding mechanisms, of a binder, ruffling mechanism comprising a ruffling blade having a range of movement adjacent said binder, and a work-support provided with a guide-rib disposed 60 beneath the range of movement of and in operative relation with said ruffling blade and inclined to its direction of movement and toward said binder.

4. In a sewing machine, the combination 65 with stitch-forming and feeding mechanisms, of a binder formed with spaced upper and lower laterally extending channel members, ruffling mechanism comprising a ruffling blade having a range of movement adjacent said binder, and a work-supporting plate disposed beneath said ruffling blade adjacent the binder and having in its lower face a clearance recess to accommodate the lower channel member of said binder and 70 upon its upper face a plurality of convergent guide-ribs inclined toward said binder and adapted to support a body fabric under the action of the ruffling blade.

5. In a sewing machine, the combination 80 with stitch-forming and feeding mechanisms, of ruffling mechanism comprising a vibratory arm, actuating means therefor, a swinging arm, a detachable connection between said arms, means for retracting said 85 swinging arm when detached, a ruffling blade carried by said swinging arm, and means for directing the ruffling blade away from the work when said swinging arm is retracted.

In testimony whereof, I have signed my name to this specification, in the presence of two subscribing witnesses.

FRANS T. STRÖBECK.
